UNITED STATES PATENT OFFICE.

FRANCIS S. WALTERS, OF WILKINSBURG, AND BURWELL F. DAY, OF SWISSVALE, PENNSYLVANIA, ASSIGNORS TO GEORGE F. VORHAUER, OF BEAVER FALLS, PENNSYLVANIA.

AUTOMATIC FILE CLEANING AND SHARPENING MACHINE.

Application filed January 2, 1924. Serial No. 684,000.

Our invention relates to file cleaning and sharpening machines and, more particularly, to an automatic machine which is capable of cleaning and sharpening files in relatively 5 large quantities without the attention of a skilled operator.

It is among the objects of our invention to provide an automatic file cleaning and sharpening device which shall be of simple, 10 durable and rugged mechanical construction, which shall embody a minimum number of mechanical movements and which shall carry out the steps of cleaning, sharpening and drying files automatically in an expedient 15 and efficient manner.

The cleaning and so-called "sharpening" of metal-cutting files, as heretofore practiced, consists of manipulating the file with the back of its cutting edges against a high- 20 pressure steam and sand blast, which functions to clean out the cuttings between successive cutting edges by de-greasing the file with the hot steam and mechanically removing the cuttings by means of the sand blast, 25 the latter also functioning to even the cutting edge which, in that respect, constitutes the sand blast a sharpening process. The sand blast is subsequently shut-off and the file is subjected to the steam blast for the 30 purpose of cleaning and drying the same.

The success of this process was largely dependent upon the skill of the workman, both as to the manner of manipulating the file and as to the duration of time necessary to 35 complete the operation, and, as a result, the quality of the work produced was greatly deficient.

Our present invention is directed to a machine for automatically conducting the necessary 40 functions of the file cleaning and sharpening operations, the mechanism being designed to provide absolute control of the manipulation of the file and the steam and sand blast by providing positive relative movements of the file members and the steam and sand blast nozzles.

Our device further adapts itself to quantity 45 production as a multiple of files can be acted upon contemporaneously leaving the operator free to devote himself entirely to the removal and replacement of the files in the tool holder.

In the accompanying drawings, constituting a part hereof, and in which like reference characters designate like parts,

55

Figure 1 is a view, partially in section and partially in elevation, of an automatic file cleaning and sharpening machine embodying the principles of our invention;

Fig. 2 is a rear end elevational view thereof; and

Fig. 3 is a front end elevational view thereof, showing the relative disposition of the several co-operating parts.

Referring to Fig. 1, the device therein illustrated comprises a frame 1, having a flanged base 2, provided with openings 3, adapted to receive screw bolts or the like for anchoring the frame securely on a suitable foundation. A turret-head 4 is rotatably mounted by a pivot pin 5 in an opening 6 of the frame member 1, the turret being provided with a plurality of slotted openings 7, which are angularly disposed in stepped relation to adapt them to receive work-holder 75 slide arms 8, which are movably mounted therein. The ends of the slides 8 are provided with an angular portion 9, on which a tool or work-holder 10 is mounted.

A plurality of nozzles 11 are secured on 80 the end frame portion 12 of the frame 1 in a manner to provide pivotal movement thereof, the nozzles 11 being secured on a movable head 13 that is pivotally mounted on the frame 12 and connected by a crank 14, which 85 is connected at one end to the crank pin 15 of an eccentric drive wheel 16. The nozzles 11 are connected to a pipe-line 17 leading to a source of high-pressure steam (not shown) and flexible hose 18 is connected to the nozzles 11 to communicate with a sand supply (not shown).

A drive shaft 20 and a screw shaft 21 are journaled for rotation in the frame 1 with their axes in parallel relation, the shaft 20 95 having a pulley 22 secured on the end thereof to provide a driving connection with a motor or other type of prime mover (not shown).

A gear wheel 23 is keyed on the shaft 20 100 and a gear wheel 24 is mounted on the screw shaft 21 in co-operative alinement with the wheel 23. The screw shaft 21 is provided with a keyway 25 and the gear wheel 24 with

a key 26 to provide a movable spline connection with the screw shaft 21.

A gear wheel 27 is mounted in screw-thread engagement with the shaft 21, and a clutch gear 28, having a relatively wide face, is mounted for rotation on the drive shaft 20. The gear 28 is provided with a clutch collar 29, adapted to receive a pair of trunnion members 30 of a shifting yoke 31, which is pivotally connected to the frame 1.

A clutch collar 32 is secured, by a pin 33, or in any suitable manner, to the drive shaft 20, and a clutch member 34 is disposed on the shaft 20 and fixed in the frame member 15 by a set screw 35. A shifting lever 31 is pivotally connected at its end 36 to a lever arm 37, which is resiliently connected to a shifting arm 38 that is secured to one end 20 of a shifting lever, 39. The lever 39 is extended through an opening 40 of the frame 1, and a friction pad 41, to take up slack, and one end 42 of the lever 39 is diverted at right angles for the purpose of engaging a plunger 43 that co-operates with a spring 25 clamp 44. A pair of adjustable stops 45 and 46 are mounted on the shifting lever 39.

A guide rod 47 is rigidly secured at one end to the frame 1 by a plurality of set screws 48, and a guide arm 49, having a 30 clamping screw 50 provided in its upper portion to engage the work-holder slider arms 8, is slidably mounted on the guide arm 47 and secured to the end of the screw shaft 21 by a screw nut 51. The extended 35 portion 52 of the guide arm 49 is provided with an opening 53 to receive the shifting lever 39.

A line shaft 55 is journaled in the frame 1 and end frame 12, and a plurality of 40 sheave wheels 56 and 57 are respectively secured thereto. The hub portion of the gear wheel 24 is provided with a groove 58 to receive a round belt 59 to connect the gear wheel 24 with the wheel 56, and a similar 45 belt connection 60 is provided for the wheel 57 and the crank wheel 16 (Fig. 3) to actuate the latter. A guard 61, having an opening 62, is mounted in proximity to the end frame 12 and connected therewith by a 50 mounting bracket 63.

The operation of this device is briefly as follows: A plurality of files F are secured in the work-holders 10, as shown in Figs. 1 and 3, and the slide arm 8 is secured to the guide arm 49 by the clamping screw 50. The drive shaft 20 is actuated to rotate, which actuates the gear wheel 24 at a reduced speed and, with the position of the clutch gear 28 as shown in Fig. 1, the gear 28 being in engagement with the driving clutch 32, the gear wheel 27 is rotated. By virtue of the screw-thread engagement of the gear wheel 27 with the shaft 21, the latter is moved axially, which causes a lateral movement of the guide arm 49 on the

rod 47, to effect a corresponding movement of the slide 8 in the turret-head 4, causing the work-holder 10 and the files secured therein to be moved along the top of the nozzles 11.

When the extended portion 52 of the guide arm 49 strikes the stop 45 of the shifting lever 39, the latter is actuated, which pivots the clutch lever 31 to disengage the clutch gear 28 from the clutch 32 and engage the same with the stationary clutch 34. In this position, the gear 28 is fixed against rotation, thereby holding the gear wheel 27 stationary on the screw shaft and, since the gear wheel 24 is rotating at all times, it will rotate the shaft 21 against the threaded engagement with the stationary gear 27, thereby causing the shaft to move axially in the opposite direction until the clutch gear 28 is again reversed by the engagement 85 of the guide arm 49 with the stop 46 of the shifting lever 39.

The ratios of the gear wheels are such as to obtain one-half the speed of travel of the tool-holder 10 when driving through the spline gear 24 of the screw-thread gear 27 for the purpose of obtaining a slow rate of travel of the file surface over the mouth of the nozzle 11 during the cleaning and sharpening operation; that is, while the steam and sand blast are turned on in full force. When the nozzles have reached the end of the file F, as shown in Fig. 1, the shifting lever 39 engages the plunger 43, which forces the spring clip 44 against the hose 18, thus shutting-off the sand blast. At this point, the direction of motion of the work-holder 10 is reversed, and the file traverses along the mouth of the nozzle at double the speed of the cleaning and cutting operation, and, since the sand blast is shut off, the steam emitted from the nozzle functions to further clean and dry the files.

During this cycle of operation, the nozzles 11 are rapidly oscillated across the face of 110 the files by the crank connection with the crank pin 15, to insure thorough cleaning of the file slots, and this oscillatory motion of the nozzles further permits using smaller nozzles and less steam and sand, as they can 115 be made to cover more area than stationary nozzles.

When a set of files have been cleaned and sharpened in the manner described above, the clamping screw 50 is disengaged with 120 the work-holder slide arm 8, and the latter is replaced by another work-holder carrying another set of files by rotating the turret-head 4. The machine is then set to repeat the operation and the operator may remove 125 and renew the finished files at his leisure.

It is evident, from the above description of our invention, that an automatic file cleaning and sharpening machine, as described herein, functions to expediently and 130

efficiently clean and sharpen files at a minimum cost in relatively large quantities and of uniform quality.

Although we have described a specific embodiment of our invention, it will be obvious to those skilled in the art that a machine embodying the mechanical movements herein described is not restricted for use to the process of cleaning and sharpening files, but may be utilized for any purpose in which a co-ordination of such relative mechanical movements are applicable and desirable, and it is further obvious that various modifications may be made in the details, proportion and design of the several co-operating parts without departing from the principles herein set forth.

We claim as our invention:

1. A file sharpening machine comprising a base, a turret rotatably mounted thereon, a plurality of work holders slidably mounted in said turret, a guide arm adapted to engage said holders, a plurality of nozzles in co-operative alignment with said guide arm, a steam and a sand-blast conduit connected to said nozzles, means for actuating said guide arm to provide lateral movement of said holders, and means for oscillating said nozzles.
2. In a file sharpening machine the combination with a work holder, of a movable blast-nozzle, an axially movable guide arm for said holder, an actuating mechanism for said guide arm comprising a rotatable shaft and gear wheels, the latter being connected to said guide arm, and means associated with said mechanism for imparting an oscillatory movement to said nozzle.
3. In a file sharpening machine the combination with a work holder, of a movable blast-nozzle, an axially movable guide arm for said holder, an actuating mechanism for said guide arm comprising a rotatable shaft and gear wheels, the latter being connected to said guide arm, means for imparting a reciprocatory movement to said work holder, and means associated with said mechanism for imparting an oscillatory movement to said nozzle.
4. In a file sharpening machine the combination with a work holder, of a blast-nozzle, an axially movable guide arm for said holder and means for imparting a reciprocatory movement to said guide arm, said means comprising a drive shaft and a screw shaft journaled for rotation in a

frame, a gear wheel mounted on said screw shaft having a spline connection therewith, a gear wheel keyed on said drive shaft co-operatively engaged with the first-named wheel, another gear wheel mounted on said screw shaft in screw-thread engagement therewith, a clutch gear rotatably mounted on said drive shaft in co-operative engagement with said last-named screw shaft gear, a clutch secured to said frame and actuating means for said clutch gear to alternately engage said clutch gear and clutch.

5. In a file sharpening machine the combination with a work holder, of a blast nozzle, an axially movable guide arm for said holder and means for imparting a reciprocatory movement to said guide arm, said means comprising a drive shaft and a screw shaft journaled for rotation in a frame, a gear wheel mounted on said screw shaft having a spline connection therewith, a gear wheel keyed on said drive shaft co-operatively engaged with the first-named wheel, another gear wheel mounted on said screw shaft in screw-thread engagement therewith, a clutch secured to said frame, and automatic actuating means associated with said screw shaft for shifting said clutch gear to alternately engage said clutches.

6. A file sharpening machine comprising a turret head rotatably mounted in a frame, a plurality of tool-holders slidably mounted in said head, a plurality of nozzles oscillatably mounted on said frame, a drive shaft and a screw shaft journaled for rotation in said frame, a clamp secured to said screw shaft to engage said tool holders, a gear wheel mounted on said screw shaft having a spline connection therewith, a gear wheel keyed on said drive shaft co-operatively engaged with the first-named wheel, another gear wheel mounted on said screw shaft in screw-thread engagement therewith, a clutch gear rotatably mounted on said drive shaft in co-operative engagement with said last-named gear, a clutch secured to said drive shaft, a clutch secured to said frame, a shifting device actuated by said clamp to actuate the said clutch gear and a crank connecting said nozzles to oscillate the same.

In testimony whereof, we have hereunto subscribed our names this 11th day of December, 1923.

FRANCIS S. WALTERS.
